Inventor,
James Barr Cockburn
by B. Anger, Atty.

UNITED STATES PATENT OFFICE.

JAMES BARR COCKBURN, OF FALKIRK, SCOTLAND.

MEANS FOR ATTACHING BUSHES OR SOCKETS TO PLATELIKE BODIES BY FLANGING.

Application filed April 28, 1921. Serial No. 465,827.

To all whom it may concern:

Be it known that I, JAMES BARR COCKBURN, a subject of the King of Great Britain and Ireland, of 5 Learmouth Street, 5 Falkirk, Scotland, engineer, have invented certain new and useful Improved Means for Attaching Bushes or Sockets to Platelike Bodies by Flanging, of which the following is a specification.

10 My invention relates to means for internally supporting a socket while it is being flanged to secure it in a hole in a plate and has for its object to simplify and cheapen the process.

15 In carrying out my invention, I provide a supporting mandrel of three or more sections, held in position by a suitable flanging die which is suitably fixed to the body, the lower portion of which is reduced in 20 diameter and tapered, while the internal diameter of the die is formed to suit the tapered portion of the body. The bottom part or section of the die is provided with a recess which contains a spring which is retained in position by a cap and screw.

25 In order that my invention may be properly understood and readily carried into effect, I have hereunto appended one sheet of drawings, of which—

30 Figure 1 is a section through top die.

Figure 2 is a section of Figure 1 through line α , γ .

Figure 3 shows in dotted lines of the socket finished flanged to the plate.

35 Figure 4 is a section of the bottom die.

Referring to the drawings, A is the supporting mandrel which is in three parts and B the flanging die which at the same time holds the sections of the support mandrel 40 together. C¹ is the conical part of the body C. D is the bottom die, while E is the spring carried in the recess in the bottom die D, and F is the cap and G the screw holding the spring in its place.

45 The operation is as follows:—

The socket H is placed in the plate J and the whole then placed in position on bottom

die D. The body C is then brought down, when the supporting mandrel A enters the hole in the socket H and is prevented from collapsing by the conical part of the body C¹ and the resistance exerted on the supporting mandrel A by means of the spring E, pushes it against the taper C¹ on the body C, and expands the supporting mandrel A, thus keeping the hole of the socket H from being distorted, while the flanging is taking place. The body C now advances when the flanging die B comes into contact with the socket H and flanges it over on to the plate J. On the upward motion of the body C, the pressure is released from the supporting mandrel A which allows it to come down and collapse and enables the socket H to be easily removed.

Claims.

1. A diametrically expandable mandrel, a die by which said mandrel is carried, a body to which the die is secured, and having means, active during a working stroke of the die, to expand the mandrel, a counter die, and a spring therein, arranged to coact with said expanding means during a working stroke of the die.

2. An annular, diametrically expandable mandrel, comprising separable segments and having a tapered bore, a die by which said mandrel is carried and in which said die is axially movable, a body to which the die is secured and having a tapered projection arranged to operate in the tapered bore of the mandrel, to expand the latter during a working stroke of the die, a counter die, and yieldable means in the counter die to cushion the mandrel during the working stroke of the die and thereby coact with the said tapered projection in expanding the mandrel.

In testimony whereof I affix my signature in presence of two witnesses.

JAMES BARR COCKBURN.

Witnesses:

O. L. LIDDLE,
JOHN TRAIN LIDDLE.
